UNITED STATES PATENT OFFICE.

ALFRED KAUFMANN, OF PHILADELPHIA, PENNSYLVANIA.

WHEEL.

Application filed July 29, 1924. Serial No. 728,885.

To all whom it may concern:

Be it known that I, ALFRED KAUFMANN, a citizen of the United States, residing in Philadelphia, Pennsylvania, have invented 5 certain Improvements in Wheels, of which the following is a specification.

One object of my invention is to provide in a quick and economical manner a disc wheel which will be particularly suitable 10 for toy vehicles.

Another object is to so make my improved wheel that it will be strong and durable even though made out of exceptionally thin sheet metal.

15 A further object is to so form said wheel that it will readily allow attachment of a rubber tire and will run true.

These objects and other advantageous ends which will be set forth hereinafter, I 20 attain in the following manner, reference being had to the accompanying drawings, in which

Figure 1 is an inner face view of one of two similarly formed disc sides of my 25 improved wheel,

Figure 2 is a central section of Figure 1,

Figure 3 is a face view of a flat metallic 30 cut strip illustrating one stage in the operation of making a disc-binding ring which forms a part of my present invention,

Figure 4 is a face view of the strip shown in Figure 3 illustrating another stage in the operation,

Figure 5 is a face view of the finished 35 ring,

Figure 6 is a face view of a reinforcing washer for the discs, which I preferably employ,

Figure 7 is a cross section of the wheel 40 in one of the stages of manufacture,

Figure 8 is a cross section of the completed wheel,

Figure 9 is an enlarged fragmentary section of a portion of Figure 7,

Figure 10 is an enlarged fragmentary 45 section of a portion of Figure 8,

Figure 11 is a view showing the blank from which the hub bushing is made, and

Figure 12 is a face view of the hub bushing 50 before its ends are beaded or spun.

In making my improved wheel and by reference to the accompanying drawings, two similarly formed discs 15 and 16 are made by pressing them by dies from sheet 55 metal. Each of these discs has a bulged

portion 17 which includes a flat central portion 18. When the discs come from the dies they have holes centrally located within the portions 18 of diameters shown by the dot-and-dash line circle 19 in Figure 1. 60 A washer 20, of a shape clearly shown in Figure 6, is then placed against the outer surface of each of the portions 18, and the metal of the portions 18 is punched or pressed to project a flange 21 through the 65 hole 22 of the washer, thus causing the hole 19 to be enlarged, and to securely hold the washer to the portion 18 in a position surrounding the flange 21. This action is done on each of the disc sides of 70 the wheel. Each of the washers 20 has a notch 23, and in punching the flanges 21 through the washers, portions 24 of the flanges 21 are bulged so as to fit within the notches 23, thus forming keys preventing 75 relative rotation between the discs and the washers. Also when the discs 15 and 16 are pressed into the shape by the dies as previously described, ears 25 are cut and pressed outwardly at a slant as shown in Figures 80 1 and 2, and these ears serve as retaining means for hub caps such for example as the hub cap indicated at 26 in dot-and-dash lines in Figure 8. It will be noted that the hub cap is applied to the outer side of the 85 wheel in accordance with the side of the vehicle to which the wheel is attached. In applying the hub cap it is merely necessary to bend two of the four ears at right angles to the portion 18 after which the flange of 90 the hub cap can be slipped under the other two of the ears and then the two ears which had previously bent outward can be bent back again into their normal positions securing the hub cap in place. This latter 95 action of course is done after the wheel is applied to the vehicle.

It has been previously described how the disc sides are made and I will now describe the continued stages in the manufacture 100 of the wheel.

A flat strip of thin metal, which is preferably slightly resilient, is cut in the form shown in Figure 3, said cutting at one end including a notch 27 and at the other end 105 a tongue 28. The end having the tongue 28 projecting therefrom is notched at 29 to provide scarf'd or beveled edges 30 and a projecting portion 31 of greater width than the tongue 28. After the strip has been 110

cut, as described in connection with Figure 3, it is rolled by passing it between rollers which imparts a curvature to the strip and at the same time makes the strip channel-form producing outwardly extending flanges 32 on opposite sides as shown in Figure 4. Furthermore, said rolling causes the strip to assume a ring formation or nearly so to move the slotted end toward the 10 end which has the tongue 28 thereon. The tongue 28 is then passed through the slot 27 and bent under as shown in Figure 5, the portion 31 overlapping the opposite end of the strip and fitting snugly within the 15 channel to produce the ring.

Each of the discs 15 and 16 has an annular groove 33 which is formed by the dies when the discs are first pressed as previously described. Said grooves 33, as shown in cross section in Figures 2, 7 and 9, provide annular shoulders 34 which in cross section extend substantially at right angles to the inner surface portions 35 or in other words, are substantially parallel with the axes of the discs. Furthermore, the grooves 33 are produced at the outer edges of the discs so that the outer edge portions 36 of the discs are substantially parallel to the shoulders 34. The inner surface of the portion 37 of the ring is of a diameter similar to the diameters of the shoulders 34 of the discs so that when two discs are placed together in the position shown in Figures 7 and 9, the portion 37 of the ring will snugly fit against the shoulders with the flanges 32 within the respective grooves 33. By having the shoulders 34 as illustrated, two of the disc sides can be quickly and accurately slid into position so that the flanges 32 will be embraced by the walls of the grooves 33 with the portion 37 firmly mounted in position surrounding and contacting with the shoulders 34.

I preferably make the hub 38 by first forming a bushing 39 as shown in Figure 12, the bushing being rolled from a piece of metal cut and stamped in the form shown in Figure 11, said piece of metal having one edge beveled as shown at 40, the beveling forming an indentation while the opposite end 41 is beveled outwardly so that when the metal is rolled into the form shown in Figure 2, the edges 40 and 41 will form a parting extending at a slant as clearly illustrated. I also preferably provide the hub bushing with two rows of lugs 42 and 43, said lugs being pressed from the material. One of the lugs in each row includes an extension 44 and these extensions are adapted to project within the notches 45 formed by the portions 24 of the flanges 21. When the hub bushing is inserted through the holes provided by the flanges 21, the lugs 42 and 43 form abutments for the portions 18 of the discs and the opposite

ends of the bushings are spun or beaded to provide end flanges of greater diameter than the diameters of the flanges 21. Thus the discs are kept from moving toward each other or away from each other due to the 70 hub structure.

One of the important stages in the construction of my improved wheel, after the ring has been inserted between the discs as shown in Figure 7, is to spin or bead the 75 outer edge portions of the discs so as to lock the flanges 32 within portions of the discs as shown in Figures 8 and 10. This spinning action is accomplished by maintaining the discs in the spaced position shown in 80 Figure 7, either by first beading or spinning over the opposite ends of the hub bushing as previously described or by keeping said discs in said spaced position by other means. During the spinning of the outer 85 portions of the discs to interlock the flanges 32, portions of the discs are pressed to close the grooves 33 and to force the edge portions 36 inward toward the portion 37 of the ring, the outer parts 46 of the discs also 90 being pressed during the spinning action so that the flanges 32 are compressed between the portions 36 and 46 as clearly shown in Figure 10. I preferably employ the hub as a holding means for the discs during 95 said latter spinning action, in other words, I preferably insert the hub and bead or spin its outer edges so that the final stage is the spinning of the peripheral parts of the discs and compression of the flanges 100 32. Furthermore, this action causes the truing of the wheel and the space 47 will have smooth walls allowing a rubber tire to be inserted therein, said rubber tire not being illustrated in the drawings. 105

By forming the parting of the hub bushing by the edges 40 and 41, the parting will be at a slant and consequently at no time will the weight of the vehicle be upon the entire parting as would be the case if said 110 parting extended from end to end of the bushing in a straight line.

In manufacturing my improved wheel, it is an easy matter to interlock the ends of the ring, insert the hub bushing, and move 115 the discs together so as to embrace, within the grooves 33, the flanges 32. The discs can then be held together either by beading over the ends of the bushings or by other means, and the peripheral portions of the 120 discs can then be spun to interlock and compress the flanges of the ring. Furthermore, by making the ring of metal which is slightly resilient, the tendency is for the ring to try to open up and in so doing causes the tongue to bear against the wall of the slot and the ring will be under slight tension, thus allowing it to be handled without fear 125 of opening up or accidental movement of the adjacent end portions. 130

Having thus described my invention what I claim as new and desire to secure by Letters Patent is:

1. A disc wheel of the character described including two sides with annular grooves near their peripheries, the portions of the walls of the grooves nearest the axis providing annular shoulders; and a ring having a central annular portion with parts thereof extending into said grooves and fitting against said shoulders, said ring being surrounded by and compressed between the walls of said grooves at a position outwardly from said shoulders.
2. A wheel of the character described including a rim made of strip material having outwardly projecting side flanges providing a tire-receiving channel, one end portion of said strip material having a slot, the other end having a portion projecting beyond the ends of said flanges and forming a hook, said hook engaging through said slot.
3. A wheel of the character described including a rim made of bent strip material and having flanges connected to the sides of the wheel to provide an outer channel, the ends of said strip being hooked together.
4. A disc wheel of the character described including a disc having a central hole surrounded with a flange; and a reinforcing washer surrounding the flange and having a notch, a portion of the flange extending into said notch.
5. A wheel of the character described including a disc having a central hole surrounded with a flange; a reinforcing washer surrounding the flange and having a notch, a pressed portion of the flange extending into said notch; and a hub extending through the hole provided by said flange and having a lug fitting within said pressed portion of the flange whereby the disc, washer and hub are held against relative movement.
6. A wheel of the character described including two discs with their central portions having holes surrounded by flanges, each of said flanges having a depression and a hub having portions extending through said holes and being beaded at their outer ends to provide outer flanges of greater diameter than said holes whereby the central portions of the discs are prevented from spreading, said hub having lugs pressed outwardly therefrom for engaging the inner surfaces of said central portions of the discs, certain of said lugs having parts which extend within said depression in the flanges to prevent relative rotation between the discs and hub.
7. A disc wheel including a central portion for the hub and a plurality of ears cut and pressed outwardly to allow a hub cap to be secured to said central portion.

In testimony whereof, I have signed my name to this specification.

ALFRED KAUFMANN.
